UNITED STATES PATENT OFFICE.

IRA J. HOLLENSBE AND EARL F. SHELLEY, OF GREENSBURG, INDIANA.

HOLDER FOR BROOM HEADS.

Application filed February 25, 1924. Serial No. 695,038.

To all whom it may concern:

Be it known that we, IRA J. HOLLENSBE and EARL F. SHELLEY, citizens of the United States, residing at Greencburg, in the county 5 of Decatur and State of Indiana, have invented certain new and useful Improvements in Holders for Broom Heads, of which the following is a specification.

This invention relates to improvements in 10 holders for broom heads.

An object of the invention resides in providing a holder for a broom head formed of a single piece of sheet metal adapted for receiving the butt end of a broom head and 15 for permanently housing and retaining the same therein.

Another object of the invention resides in providing a mounting for broom heads formed of a single piece of sheet metal provided with a socket for receiving the butt end of a broom head and adapted to be received within the socket in an intimate compressed relation.

Another object of the invention resides in 25 providing a holder for broom heads formed of a compressible body adapted to receive the butt end of a broom head, the holder being compressed on said butt end for mounting and retaining said head in said body.

A further object of the invention is to provide a one piece body of sheet material formed into a socket for receiving the ring retained butt end and adapted to be compressed into intimate and interlocking relation with said retaining ring and the broom head for mounting said broom head in the holder.

The invention further comprehends other 40 objects in the construction and assemblage of the broom holder on the broom head for cooperation therewith, which is more particularly pointed out in the following description and claims directed to the preferred construction of the holder, it being understood, however, that variations may be made in these constructions without departing from the spirit and scope of the invention as described and claimed.

50 In the drawings, forming a part of this application:

Figure 1 is a side elevation of the broom holder with the butt end of the broom head mounted in assembled relation therewith to 55 form the finished broom.

Figure 2 is an end elevation of the finished

broom mounted in a holder constructed according to the present invention.

Figure 3 is a longitudinal section through the broom shown in Figure 1, illustrating 60 the manner of applying the holder to the butt end of the broom head for retaining the head therein; the position of the broom handle being also shown therein.

Figure 4 is an end view of an open end of 65 a broom holder having the separable sections thereof formed with portions adapted to interlock when the same is compressed on a broom head.

Figure 5 is a view similar to Figure 4 70 showing the end portions in interlocked relation.

Figure 6 is an end view of the holder shown in Figure 5, showing the structures in 75 co-operating compressed relation.

Figure 7 is an end view of the holder shown in Figure 4, with the sections in separated relation.

Figure 8 is a sectional view taken on the line 13—13 of Figure 1.

1 indicates a broom head of special form having the butt end 2 retained in an elongated flattened ring member 3 clearly shown in Figure 3 in locked relation, the end being rounded both transversely and longitudinally as indicated at 4, while the central portion of the broom head is stitched as indicated at 5 in the usual and well known manner.

This specially formed and ring retained 90 broom head is adapted to be fitted in a holder member 6 which forms the subject of this invention. The holder is formed in one piece, preferably from sheet material having a body 7 of socket form, to receive the ring 95 retained butt end of the broom head 1, and adapted to conform to the contour thereof to a point below the retaining ring as will be clearly observed from Figures 1 and 2.

The end or bottom of the socket portion of the body 7 is curved as indicated at 8 in the same manner as the end of the broom head indicated at 4 and the central portion of this curved end is provided with a cylindrical neck extension 9 for receiving a handle 10 adapted to be inserted through the neck 9 and having the end pointed as indicated at 11 for projection into the end of the broom head to a point beyond the section of the retaining ring so that the compression of the broom material within the retaining ring 100

105 will be increased from the central portion 110

thereof which will aid in retaining the broom handle in place in the broom head and also in securing the broom head in place in the holder 6, as the handle is inserted through 5 the neck 9 and into the broom head to a position as shown in Figure 3, under a heavy driving pressure, so that when in place, the handle is retained by the driving fit.

The open end of the body of the broom 10 holder, that is the open end of the socket portion 7 as indicated at 12 is formed with an outwardly projecting and transversely extending bead 13 forming a semi-cylindrical groove 14 on the inside of the socket 15 for receiving the retaining ring 3 of the broom head, so that when the broom holder is applied to the end of the broom head as shown in Figures 1 to 3 in particular, the binding ring 3 will seat in the groove 14 20 and effectively lock the broom head in the socket. The open end portion 12 of the body 7 is formed with separable sections 14 and 15, which are formed in separated relation as shown in Figures 6 and 7. The 25 separable sections of the outer end of the socket portion 12 of the body 7, may, if desired, be provided with oppositely directed projections 17 and 18 which are formed with similar and inwardly projected punch portions 30 19 adapted to interlock as shown in Figures 5 and 6, when the sections are compressed onto the butt end of the broom head so that a subsequent separation of the sections which would impair the mounting 35 of the broom head is effectively prevented, and the grooves 13 will therefore be effectively retained against the broom head and in housed relation with respect to the ring for retaining the head in the broom holder. 40 For additionally insuring the retention and cooperation between the end portion 12 of the body 7 and the ring 3 of the broom head, counter-sunk spots 20 are formed in the side walls adjacent ring groove 14 so as 45 to project into the broom head as indicated in Figure 8, beyond the retaining ring 3 for effectively retaining the ring 3 in the broom holder.

The interlocking projection 19 forms an 50 interlock for the separable sections 14 and 15 of the body 7 for effectively locking said sections in compressed relation on the butt end of the broom as shown in Figure 2, and is applied to the broom head, by inserting 55 the butt end of the broom head into the socket formed by the body 7 with the sections 14 and 15 in separated relation as shown in Figure 7, after which the holder with the broom head inserted is placed in a

suitable compressor for this purpose, which 60 forces the sections 14 and 15 under a substantial pressure together and into interlocking relation as shown in Figure 6, following which the handle 10 is inserted as 65 above described under a substantial pressure through the neck 9 and into the broom head as shown in Figure 3, under a substantial pressure to form a driving fit with the broom holder and the butt end of the broom 70 head, thereby producing a completed broom structure. The sewing 5 is placed on the broom after the holder and handle are assembled with relation to the head so that the completed broom ready for use will appear as shown in Figures 1 and 2 of the 75 drawings.

From the foregoing description, it will be observed that the broom holder is formed from a single piece of sheet metal or other sheet material suitable for the purpose into 80 the form shown in Figure 7, in any suitable manner such as die stamping, forming and the like, so that a subsequent compression of the separable sections as above described will apply the holder to the broom head. It will be clearly understood from the above description that a broom holder of simple form has been provided formed of one piece and having relatively compressible portions adapted for interlocking cooperation on the butt end of a broom head and for receiving a broom handle having a driving fit in connection therewith for making an assembled and finished broom.

What is claimed is:

A holder for broom heads formed of a single piece of sheet material, said holder comprising a main socket portion, a handle receiving neck extending from the central portion of said main socket portion, a pair of opposed socket forming jaws normally extending in diverging relation from the main socket portion, said jaws being provided with opposed outwardly struck beads to provide grooves to receive the binding ring on a broom head, and said jaws being provided below said head with projections adapted to overlap when the jaws are brought into socket forming relation, and cooperating means formed on said projections and adapted when the projections are brought into overlapped relation to move into locking position.

In testimony whereof we affix our signatures.

IRA J. HOLLENSEBE.
EARL F. SHELLEY.
